UNITED STATES PATENT OFFICE.

DAVID REES RICHARDS, OF ST. LOUIS, MISSOURI.

RAIL JOINT.

Application filed December 15, 1925. Serial No. 75,515.

My invention relates to rail joints, and, it is a distinct and practical improvement to overcome certain practical objections to, and defects in, rail joints of the present type.

5 The object of my present invention is to provide a rail joint which will prevent the adjacent ends of two opposed rails from up and down movement with relation to each other and to keep the head surface of the 10 rails in a plane while the wheels of an engine and cars are approaching and leaving the joint thereby eliminating the low and high joint.

A further object of the invention is to 15 provide a rail joint which will prevent fish plate bolts from wearing the holes in the fish plates which now cause loose joints.

A still further object of the invention is to provide a space key disposed in opposed end 20 slots in the web of two opposed rails to prevent up and down displacement of the ends of the rails from any cause.

A still further object of the invention is to provide means to prevent displacement of 25 the tie-key.

A further object of the invention is the provision of a rail joint which will possess advantages in points of simplicity and efficiency, and, at the same time prove itself 30 comparatively inexpensive in manufacture.

With the above and other objects in view, the invention consists in the novel features of construction, arrangement and combination of parts hereinafter more fully described and finally pointed out in the claims 35 hereto appended.

Referring to the accompanying drawings forming a part of this specification wherein like characters of reference denote similar 40 parts throughout the several views:

Fig. 1, is a perspective view of two rails disposed end to end and equipped with a rail joint embodying the features of my invention.

45 Fig. 2, is a perspective view of two opposed rails disposed end to end showing the end slots therein.

Fig. 3, is a sectional view taken on line 3-3 of Fig. 1.

50 Fig. 4, is a perspective view of the tie-key.

Fig. 5, is a perspective view of the tie-key washer.

Referring to the drawings, the reference numerals 1 and 2 designate ties while 3 and 55 4 designate two opposed rails laid end to end thereon in the usual manner.

Each of the rails 3 and 4 is provided at each end with a slot 5 in the web 6 thereof. Each slot 5 has an open end communicating with the end face of the web 6. These slots 60 5 when the ends of the rails are confronting each other, form a single transverse slotted opening 7, as clearly shown in Fig. 2.

The numeral 8 designates a pair of fish plates each being provided with a slotted 65 opening 9. When these plates 8 are fixed to the side faces of the webs of the rails by means of the usual bolts 10, the slotted openings 9 of the fish plates 8 register with the slotted opening 7 of the opposed rails 1 70 and 2, as clearly shown in Fig. 3.

Positioned within the slotted openings 7 and 9 of the rail webs and fish plates, respectively, is a splice key 11, which spans the joint space between the opposed rails 75 3 and 4.

The splice key 11 is provided with a flanged or T-head 12 at one end and is provided at its opposite end with an extended 80 screw threaded stud 13.

The reference numeral 14 designates a washer having a slotted opening 15 for receiving the studded end of the splice key 11, as shown in Figs. 1 and 3. The washer 14 is provided upon its outer face with a pair 85 of suitable opposed bosses 15', as shown in Fig. 5, against which a nut 16 clamps, which nut is carried by the screw threaded stud 13 of the splice key 11, as shown in Figs. 1 and 3 for securing the splice key against displacement.

To further insure against possible displacement of the splice key, I provide the key with a pair of vertically disposed openings 17 which receive suitable cotter pins 18. 95 These pins can be used with or without the securing nut 16, as desired. The use of either the nut 16, or the cotter pins 18, or both, it is manifest, will secure the splice key against lateral displacement.

From the foregoing description, it is evident that I provide a rail joint which will positively prevent the up and down movement of the confronting ends of two adjacent rails independent of each other due to the use of the splice key 11 passing through the slotted openings in the webs of the rails even should the bolt openings in the fish plates be slightly worn or enlarged. Both ends of the rails must yield together under 105 a load thereon by the use of my splice key 11 which unites the rails at the joint of two 110

confronting rails thereby providing a rail bond which is strong and durable, highly efficient and one which guards against loose rail joints without the use of a joint tie or the use of rail plates.

The many advantages of the herein described invention will readily suggest themselves to those skilled in the art to which it appertains.

10 I do not wish to be understood as having limited myself to the exact details of construction shown and described, but desire to have it understood that the invention I have shown in the drawings is merely illustrative, 15 as it is manifest that various minor changes may be made in the exact construction and arrangement of parts without departing from the spirit of my invention, hence I reserve the right to make any such changes, or 20 modifications as may fairly fall within the scope of the appended claims when fairly construed.

What I claim is:

1. In a rail joint construction, a pair of 25 rails each having the confronting end of its web provided with an open ended slot in register with the other, a pair of fish plates secured to the rails and each provided with a slotted opening in register with the slots 30 in the rail webs, a splice key receivable in said slots to hold the rails in true alignment, a washer having a slotted opening mounted upon one end of the splice key, a pair of spaced bosses directed from the outer face 35 of the washer and disposed above and below the slotted opening, a head for one end of the splice key, a screw threaded shank extending from the opposite end of the splice key and a securing nut carried by said screw 40 threaded shank and engaging said bosses for securing the splice key in position.

2. In a rail joint construction, a pair of

rails each having the confronting end of its web provided with an open ended slot in register with the other, a pair of fish plates secured to the rails and each provided with a slotted opening in register with the slots in the rail webs, a splice key receivable in said slots to hold the rails in true alignment, a washer having a slotted opening mounted upon one end of the splice key, a pair of spaced bosses directed from the outer face of the washer and disposed above and below the slotted opening, a head for one end of the splice key, a screw threaded shank extending from the opposite end of the splice key, a securing nut carried by said screw threaded shank and engaging said bosses and cotter keys carried by said splice key on opposite sides of said bosses.

3. A rail fastening adapted to secure the confronting ends of adjacent rails, said rails each having the end of its web portion provided with an open ended slot, fish plates secured to the webs of the rails, said fish plates having slotted openings therein in register with the slots in the webs of the rails, a splice key receivable in the slotted openings of the fish plates and the slots of the rails, a head for said splice key, a washer mounted upon one end of the splice key and engaging one of the fish plates, a pair of bosses directed from said washer, a screw threaded stud extending from the splice key and extending beyond said bosses, a nut carried by said screw threaded stud and engaging the bosses of said washer for securing the splice key against displacement and a pair of cotter pins carried by the splice plate on opposite sides of the bosses of said washer.

In testimony whereof, I have hereunto signed my name to the specification.

DAVID REES RICHARDS.
